UNITED STATES PATENT OFFICE.

VICTOR H. JENNINGS, OF WORCESTER, MASSACHUSETTS, ASSIGNOR TO MILLS WOVEN CARTRIDGE BELT COMPANY, OF WORCESTER, MASSACHUSETTS, A CORPORATION OF MASSACHUSETTS.

WOVEN CARRIER.

1,210,377.

Specification of Letters Patent. Patented Dec. 26, 1916.

Application filed June 3, 1916. Serial No. 101,451.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Carriers, of which the following is a specification, reference being had therein to the accompanying drawings.

10 The invention has relation to woven carriers on the order of those having one or more pockets and used for holding and carrying cartridges, packaged first-aid supplies, etc. Among the pocketed carriers to which 15 the invention is applicable are comprised cartridge-carriers, hospital corps belts, medical officers' belts, and others having special adaptations.

20 In the case of many pocketed carriers it is customary to insert an eyelet, gromet, or the like, into the body-web in connection with a pocket, at a point laterally adjacent the closed end of such pocket, between pockets when there are two or more, to receive the 25 engaging portion or hook of a wire hanger or suspensory device pertaining to some other piece of equipment.

One object of the invention is to provide a 30 reduced thickness of body-web, so that an eyelet, gromet, or the like, having a short barrel may be used, in order that after the eyelet, gromet or other device has been set and clenched or otherwise fastened in place there shall exist a minimum distance or 35 measurement through the hole or eye thereof from the exterior of the flange at one surface of the web to the exterior of the flange at the other surface. This minimizing of the said measurement of the eyelet or other 40 device is designed to permit the use of hangers or hooks having engaging portions of uniform or standard size in all cases, instead of special sizes thereof being necessitated in cases where the fabric-structure of 45 the pocket and adjacent portions of body-web would render the said portions thicker than usual if such portions were woven as heretofore.

Another of the objects of the invention is 50 to confer upon the closed ends of the pockets of pocketed carriers an increased expansibility which will give greater capacity to the

said closed ends, preferably such as to allow the lower or inner end of a square-ended package of a size tightly and snugly fitting 55 a pocket to be thrust more fully home into the closed end of such pocket. The foregoing objects are attained by forming a pocketed woven carrier with a body-web that is split or divided in thickness laterally adjacent the closed end of its pocket. For the purpose of facilitating the application of eyelets, gromets, or the like, to one of the divisions, alone, of the body-web, one at 60 least of the said divisions, preferably the front or outer division, is formed with a free edge. Usually both are thus formed. This permits the two divisions to be separated from each other with freedom of access to each thereof, and permits the required 65 division to be operated upon in applying the desired part or parts thereto, as in setting eyelets, gromets, and the like, and avoids the necessity of setting the eyelets, gromets, or the like in the full thickness of the body-web, 70 as heretofore. It further permits of eyelets, gromets, or other devices or special attachments being applied to either or both of the 75 divisions as may be required.

Through having the front or outer division of the divided portion of the body-web free from the back or inner division thereof laterally adjacent to the ends of the bottom of a pocket to an extent which renders the said front or outer division capable 80 of separating from the back or inner division, i. e. expanding, and through having the lower portion of the front and side walls of the pocket joined to the said movable or expansible front or outer division, the said 85 lower portions derive an increased movability and expansibility of their own, enabling the closed end of the pocket to conform more fully than heretofore to the contour of the square end of the inserted pack- 90 age.

An illustrative embodiment of the invention, and illustrative weaves for the divided or expansible body-web, are illustrated in 95 the drawings, in which latter,—

Figure 1 is a perspective of a section or portion comprising two pockets of a pocketed carrier such as is employed for hospital corps service. Fig. 2 is a view looking from

the right-hand side in Fig. 1. Fig. 3 is a view of an expanded pocket in vertical section. Fig. 4 is a view of a collapsed pocket in section on line 4, 4, Fig. 1. Fig. 5 is a bottom view of a portion of a pocketed carrier on the order of that shown in the preceding views. Figs. 6 to 9 are diagrams illustrating modes of weaving the divided web.

- 10 The particular procedure and weave followed and adopted in the production of the pockets 1, 1, and of the main part of the web-portions 2 adjacent or between successive pockets, may be as preferred and as circumstances may dictate. The pockets shown in an expanded state in Figs. 1, 2, 3, and 5 are of bellows-bottom or expansion-bottom type, *i. e.* having a bottom produced by weaving two fabric-plies 1^a, 1^b, in the form 15 of an inwardly-directed fold between the back wall and front wall of the pocket, substantially as indicated in Figs. 1 and 4, in such manner as to permit the said bottom to be pressed down and the front wall to be 20 pushed outward away from the back wall, as in Fig. 3, to thereby render the closed or inner end of the pocket roomy and capacious. The invention is particularly useful in connection with pockets of the said type, partly 25 because the warp-threads which are employed in the two fabric-plies 1^a, 1^b, constituting sections of the bottom render the body-web much thicker adjacent and between the closed ends of the successive 30 pockets than such web is elsewhere. In the drawings, the closed ends or bottoms of the pockets are located at the lower edge of the body-web or band, although in some cases the lower margin of the body-web or band 35 may project a greater or less distance below the closed ends of the pockets.

In carrying the invention into effect, the intermediate portions of body-web at opposite sides of the closed end or bottom of a 45 pocket, and between one pocket and the next in the case of two or more pockets woven side by side, are woven in the two main divisions 3 and 4, the division 3 comprising a direct longitudinal continuation of the 50 section 1^a of the infolded or bellows-bottom of the pocket, and the lower portion of the back-wall, it containing the warp-threads of which said section and said lower portion of the back-wall are composed, and the division 55 4 comprising a direct longitudinal continuation of the section 1^b of the bottom, and the lower portion of the front-wall 1^c and side walls 1^d of the pocket, it containing the warp-threads of which the said section 60 and the said lower portion of the front-wall and side-walls are composed.

It will be perceived that the division 4 is capable of being spread or opened away from the division 3. It is shown as partly

spread or opened away therefrom in Figs. 1, 65 2, and 5. This permits such relative movement of the side-walls and opposite end-portions of the bottom sections 1^a and 1^b as is necessary in order to permit the corners of the closed end or bottom of the pocket to be 70 expanded to the extent required in order to permit a square-ended package to be pushed fully home against the bottom. This construction also gives the gathered infolds at 75 opposite ends of the bottom a better capacity for being pressed down and laterally outward adjacent the side walls, so that the closed or lower end of the pocket is rendered roomier transversely of the pocket.

Each of the divisions 3 and 4 of the divided web is adapted to receive eyelets such as are shown at 5, 5, in Fig. 1. In the said figure the eyelets are shown applied to the back or under division, alone. For the purpose of enabling the application of the eyelets to be made to the desired division, in this case the back or under division, at least one of the two divisions is formed with a free margin or edge. In this instance both divisions have free margins or edges. In 80 making application of eyelets or the like to the desired division, in this instance the back or under division, the other division, in this case the front or outer division 4, is lifted away or separated at the time of making 85 such application. In the present instance the front or outer division will or may be lifted, also, to facilitate the engagement with the eyelets of the engaging portions of the hangers, hooks, or other suspensory devices 100 by means of which parts of equipment are connected with the carrier. The said front or outer division 4 in its normal position will cover and protect the said engaging portions to a greater or less extent.

The manner of weaving the two divisions of the body-web 2, and the fabric-construction, and the character of the connection of the different parts of the said divisions with each other and with the adjacent portions of the said web, may vary in practice. Thus, having reference to Figs. 6 to 9, in the said divisions, the inner plies 11^a, 11^b, thereof constituting continuations of the plies forming the sections 1^a and 1^b of the bottom of 115 each pocket, may form a simple loose infold as shown by the diagram represented in Fig. 6, which will be a continuation of the folded bottom as formed in the weaving. When the eyelets are set in division 3, or it might be in both divisions, they will hold the said infold in place in the divided portion of the body-web. Or the inner plies of the two divisions may be bound as by binder-warps 11^c to the outer plies partially, for instance 120 adjacent the free margins of the divisions, as represented by the diagram given in Fig. 7. In such case the eyelets will be set in

the solid or bound portion of division 3, or 5 separate eyelets might be set in the solid or bound portions of both divisions. Or the inner plies of the two divisions may be bound completely to the outer plies as in the diagram given in Fig. 8. In the diagrams given in Figs. 6, 7, and 8 the inner plies of the two divisions are produced by short picks of weft, the weft passing over at the 10 inner edge of one of the said inner plies from such ply to the inner edge of the other thereof so as to connect the two inner edges in the weaving after the manner of a fold just as in the case of the infolded portion of 15 the bottom of a pocket. In the diagram given in Fig. 9 the picks of weft extend into the upper portion of the web-portion 2, between the face plies of the said web-portion, and are suitably caught and bound in the 20 weaving. The precise fabric-structure or weave adopted in practice may be varied according to the special results sought to be attained, and as convenience or other needs in weaving may necessitate. The weaves 25 represented in Figs. 6 and 9 will allow the sides, bottom, and lower front corners, of a pocket to expand somewhat more completely than that represented in Fig. 7, and the latter in turn will do so more fully than that 30 represented in Fig. 8.

I have already indicated herein that a further advantage of the divided or expandable body-web is the fact that the separation of the divisions 3 and 4 from each other, 35 and the mobility of division 4, serve to accommodate the lateral displacement of the bunched and wrinkled infolded portions at the opposite ends of the bottom-fold of the pocket, as a package is forced home against 40 the bottom.

The divided or expandable body-web is not necessarily restricted to embodiment in pocketed carriers having or produced with folded or expandable pocket-bottoms. It 45 may be embodied in carriers having pockets with bottoms produced in other ways.

The main portions of the body-web, exclusive of the split or divided portion thereof, may be of any approved weave. Herein 50 a fabric-construction of two plies tied or bound together by binder-warps indicated by dotted lines at *b*, *b*, is illustrated.

What is claimed as the invention is:—

1. A pocketed carrier having the lower 55 margin of the laterally-extending web thereof externally of the pocket divided in thickness alongside the bottom of the pocket, and having the eyelet or the like which receives the suspensory device of other equipment 60 set in one only of the said divisions.

2. A pocketed carrier having the laterally-extending web thereof externally of the pocket divided in thickness into two divisions alongside the bottom of the pocket, at

least one division having a free edge or margin of its own, and at least one of the divisions furnished with the eyelet or the like device which receives the suspensory device of other equipment. 65

3. A woven pocketed carrier having the 70 laterally-extending web thereof divided in thickness laterally alongside the bottom of the pocket into two divisions respectively constituting direct continuations of the front and back of the pocket and movable 75 therewith apart from each other.

4. A woven carrier having an integral bellows-bottom pocket, and having the web externally of the pocket, at and alongside the bottom of the latter, divided into two divisions integral with and direct continuations of the pocket-front and adjacent bottom-section, and pocket-back and adjacent bottom-section, respectively. 80

5. A woven carrier having a series of 85 pockets integral therewith, and having the body-web divided in thickness at and between the successive pockets, with at least one of the divisions having a free lower margin, and also having the eyelets or the like 90 which receive the suspensory devices of other equipment set in one only of the said divisions.

6. A woven carrier having a series of 95 pockets integral therewith, and having the body-web intermediate the bottoms of successive pockets divided in thickness into two divisions respectively constituting direct continuations of the front and back of each 100 of the adjacent pockets and movable therewith apart from each other.

7. A woven carrier having a series of 105 pockets integral therewith, and having as woven a continuous longitudinal infold constituting a bellows-bottom for individual pockets, and a divided body-web composed of separable divisions between successive pockets.

8. A woven carrier having a series of 110 pockets integral therewith, and having as woven a bellows-bottom to each pocket, and between one pocket and the next a body-web divided into two separable divisions, one division comprising the warps of one pocket-bottom section and of the adjacent 115 portions of the face-walls of the pockets, and the other division comprising the warps of the pocket-bottom section and of the adjacent portions of the back-walls of the pockets. 120

9. A woven carrier having an integral expansion bottom pocket, and having the web externally of the pocket at and alongside the expansion-bottom woven in divisions separating from below upwardly, one thereof in 125 direct continuation of the pocket-front and movable therewith apart from the other.

10. A woven carrier having a plurality of

integral expansion-bottom pockets, and having the body-web alongside the expansion-bottom of the said pockets woven in divisions separable from each other, and also
5 having the eyelets or the like which receive the suspensory devices of other equipment set in one only of the said divisions.

Copies of this patent may be obtained for five cents each, by addressing the "Commissioner of Patents, Washington, D C."

In testimony whereof I affix my signature in presence of two witnesses.

VICTOR H. JENNINGS.
